UNITED STATES PATENT OFFICE.

JOHN W. TOLLAND, OF ST. LOUIS, MISSOURI, ASSIGNOR OF FORTY-FIVE ONE-HUNDREDTHS TO JOHN A. TALTY, OF ST. LOUIS, MISSOURI, AND ONE-FOURTH TO FRED POWERS, OF NORMAN, OKLAHOMA.

HOT-AIR HEATER.

Application filed May 1, 1922, Serial No. 557,699.

To all whom it may concern:

Be it known that I, JOHN W. TOLLAND, a citizen of the United States, and resident of the city of St. Louis and State of Missouri, have invented certain new and useful Improvements in Hot-Air Heaters, of which the following is a specification containing a full, clear, and exact description, reference being had to the accompanying drawings, forming a part hereof.

My invention relates to improvements in hot air heaters, and has for its primary object a heater in which a constant circulation of air is set up in each room.

15 A further object is to construct a heater in which the cold and used air of a room is taken from a point at the floor, reheated and discharged into the upper portion of the room, whereby a constant circulation of 20 air is created.

A still further object is to construct a heater wherein the air when taken from the room can be passed out through the furnace and fresh air substituted.

25 A still further object is to construct a hot air heater in which it is not necessary to place the heater in a cellar, and one which eliminates the use of hot air registers in the floor or walls.

30 In the drawings,

Fig. 1 is a fragmental vertical sectional view of several rooms, showing my device in position.

Fig. 2 is a fragmental view taken on the line 2—2 of Fig. 1.

Fig. 3 is a vertical front view of the heater with parts broken away and in section.

Fig. 4 is a section taken on the line 4—4 of Fig. 3.

Fig. 5 is a section taken on the line 5—5 of Fig. 3.

Fig. 6 is a vertical section of the heater with the casing removed.

45 Fig. 7 is a top plan view of the sub-heater made use of.

Fig. 8 is a vertical cross section taken on the line 8—8 of Fig. 7.

Fig. 9 is a top plan view of the base.

50 Fig. 10 is a fragmental horizontal cross section of the suction pipes, showing the dampers located therein.

Fig. 11 is a perspective view of one of the gates made use of.

Fig. 12 is an enlarged vertical section 55 through one of the air pipes, taken on the line 12—12 of Fig. 1.

Fig. 13 is a perspective view of one of the air ducts leading to the sub-heater; and

Fig. 14 is a horizontal section of the air 60 chamber, showing a modified construction.

In carrying out my invention, 14, 15, and 16 represent the rooms of a house, and 17 the attic. The rooms are divided by means of walls 18 and have floors 19 and 20, and 65 a ceiling 21. Within the room 14 is placed the heater which consists of a base 22 which is provided with legs 23 which support it at a predetermined distance above the floor 19. The underside of the base 22 is provided with a downwardly projecting flange 24 to which is secured an air chamber 25. Connected to this air chamber are a plurality of air pipes 26, 27, 28, and 29. These 70 air pipes are provided with openings 30, in which are located air gates. These air gates are provided with a solid portion 31, and a reticulated portion 32, and are mounted in slides 33 secured to the interior of the air pipes. The air gates are also provided with a handle 34, by means of which they can be moved forward and backward in the slides, so as to open and close the 75 openings 30. Formed integral with the base 22 is an ash pit 35. This ash pit is provided on its upper surface with a projecting flange 36, into which the fire pot 37 of the furnace fits. The base 22 is also provided on its upper surface with a flange 38, around which the casing 39 fits. The 80 ash pit 35 is also provided with a collar 40, to which is fitted a pipe 41. Mounted on the firebox 37 is a casing 43, which is provided with an extension 44 for the admission of fuel. Formed integral with the casing 43 are a plurality of projecting fins 45. These fins are spaced apart and are for the purpose of permitting a more rapid radiation of heat from the casing. This casing is also provided with a flue 46 which projects through the casing 39, and to which is secured a pipe 47 for conducting the products of combustion into the chimney 48. Mounted on the casing 43 is a casing

85

90

95

100

49 which is closed at its top, with the exception of an opening 50, and in this opening is located a sub-heater, which consists of a cylindrical casting 51, open at its upper end. This upper end is provided with a flange 52 which rests on the casing 49. The sub-heater is also provided with integrally formed ribs 53 which project inwardly and are for the purpose of radiating heat, as the 10 sub-heater is located in the hottest part of the furnace. The sub-heater is also provided with openings 54 to which air ducts 55 are secured. These air ducts extend through the casing 49 and are provided with a projection 56 which catches a certain amount of air housing within the casing 39 and conducts it into the sub-heater. Mounted on the upper portion of the casing 39 is a top 15 57 which leads to a pipe 58. This pipe is in turn connected to an air pipe 59 extending along the ceilings of the rooms. The pipe 59 is also provided with openings 60, in which air gates 31 are mounted. The 20 construction and mounting of these air gates is precisely the same as the air gates mounted in the pipes 26, 27, 28 and 29. Secured within the casing 43 is a water 25 heater 61, to which pipes 62 and 63 are connected. These pipes leading to the hot water tank 64.

It will be noted from the drawings that the pipe 29 terminates in the room 14, the pipe 27 in the room 15, the pipe 28 in the room 16, while the pipe 26 extends upward through the ceiling 21 and floor 20 into the room 17. The pipes just referred to are preferably constructed rectangular in form and are designed to take the place of a base board or a wash board around a room. 30 In other words, when my device is installed, the unsightly pipes are done away with, as the pipes used by my device are ornamental in form and do not detract from the appearance of the room.

45 I may if desired eliminate the pipe 59 and allow the hot air to escape into the room or hall, and enter the various rooms to be heated through the doors or transoms, or by means of ventilators installed in the partition walls between the rooms.

The circulation of air is accomplished as follows:

50 After the fire has been built, the air within the casing 39 becomes heated and rises. This naturally creates a suction in the pipes 26, 27, 28, and 29. By opening the air gates within these pipes, air is drawn into them from the floor of the room, which air becoming heated, also rises upward and continues to draw air from the various rooms. Now in the event the pipe 55 59 is utilized, the air gates therein are opened and the heated air passes out through the reticulated portions 32 into the rooms, and as it becomes chilled, descends,

where it is again drawn into the pipes along the floor. When sweeping the room, the dampers 42 are lowered into the position indicated by dotted lines in Fig. 3, which closes off the entrance of air into the air chamber 25, and allows the air to pass through the pipe 41 into the ash pit 35, from where it is drawn upward into the fire and then passes through the chimney. After the dampers 42 have been again closed, the air enters the chamber 25 and passes upward through the openings 65 formed in the base 22, which permits it to circulate around the furnace proper.

70 It will be noted that the sub-heater is hung in the upper portion of the furnace and extends downward therein so that it receives heat directly from the fire. The air ducts having the projection 56 project into the passage way 66 between the heater proper and the casing 39, catching a certain amount of air when it rises, and conduct it into the sub-heater where it is still more highly heated. In this way, the efficiency 75 of the heater is increased inasmuch as it is given a greater amount of radiating surface. I may also form fins on the fire pot 80 37 and the section 49.

It will be noted in connection with these fins that they are interrupted and staggered so as to retard the flow of air and also bring it in contact with a greater amount of heated surface.

85 My furnace can be constructed to utilize 100 various kinds of fuel, such as wood, coal, oil, and the like. Another feature of my device is that a considerable amount of saving fuel is accomplished by means of the circulation, since the warm air does not have to be forced into the rooms, but is drawn therein by means of the suction created through the pipes extending along the floor.

90 In the modified construction shown in Fig. 14, the air chamber 25 is divided into 110 a number of compartments by means of partition walls 67. The number of compartments corresponding to the number of suction pipes. When this structure is utilized, it is also necessary to divide at least a portion of the space 66 into a corresponding 115 number of compartments.

95 This construction is preferable when long suction pipes are used, so that each pipe will 120 get an equal amount of suction, because if these separate compartments were not present, there would be a possibility of the shorter pipes receiving more suction than the long pipe, and result in an unequal heating of the rooms.

Having fully described my invention, 125 what I claim is:

A heater comprising a base provided on its lower surface with a flange, an air chamber secured to said flange beneath the base, an ash-pit integral with said base and lo- 130

cated on the upper face thereof, a flange integral with said base surrounding and spaced apart from said ash-pit, a flange integral with the top of said ash-pit and surrounding the opening formed through said top, a fire pot supported on said ash-pit and within said flange, a hollow cylindrical casing mounted on said fire box, a cylindrical casing closed on its upper end formed on said first mentioned casing, a casing surrounding said ash-pit, fire box and first mentioned casings and spaced apart therefrom, said last mentioned casings being held in position on the base by the flange surround- 15
ing the ash-pit, a bell shaped top located on said last mentioned casing, a pipe secured to said top, a second pipe connected to said first mentioned pipe, said second mentioned pipe extending into various rooms and being provided with a plurality of valve controlled openings, and a plurality of valve controlled pipes connected to said air chamber for drawing air to certain rooms, whereby a constant circulation of air is permitted. 20
In testimony whereof, I have signed my name to this specification. 25

JOHN W. TOLLAND.
